UNITED STATES PATENT OFFICE

FRANCIS X. MALOCSAY, OF UPPER SADDLE RIVER, NEW JERSEY, ASSIGNOR TO INTERNATIONAL BANDING MACHINE COMPANY, A CORPORATION OF NEW YORK

CIGAR BANDING MACHINE

Application filed June 16, 1925, Serial No. 37,464. Renewed November 29, 1930.

This invention relates generally to a cigar banding machine, and more particularly to a machine for applying bands to cigars, and has for its object to provide means whereby 5 unguammed bands may be used in the magazine of the banding machine; to rapidly remove the bands from the band magazine, and arrange to apply gum thereon; to rapidly and accurately apply said bands to cigars and 10 secure their overlapping ends together without damage or injury to the cigar or to the bands; and so to co-ordinate the mechanism that the gumming or adhesive mechanism will not function unless a band is in position 15 to be moistened or have adhesive applied thereto.

A further object of my invention is so to co-ordinate the mechanism as to reduce the number of operations necessary to apply the 20 band and thereby increase the production and reduce the cost of applying the bands to the cigar.

A cigar is a very brittle and fragile article which can be easily crushed, and its wrapper 25 injured and destroyed. The band which is wrapped around the cigar and not pasted thereon, is a fragile, flimsy paper article generally embossed, being small, of irregular shape and varying in length and width. 30 These cigar bands have to be handled in a very special way so that they will be withdrawn one at a time from a pile of bands with accuracy, and with a mechanism that will not injure the band. The apparatus for 35 applying the band must be of such a character as to permit bands of various sizes and shapes to be used. The band mechanism must be so organized as to accommodate bands of various sizes and shapes. The mechanism for applying gum or adhesive to one end of the band must work accurately and rapidly and must be so constructed that it will not apply gum except to a portion of the band 40 and in no manner apply gum to the machine or mechanism, and mechanism must be devised so that the gumming or adhesive mechanism will not function and be rendered ineffectual if no band is in position to receive 45 gum or adhesive, and the mechanism for ap-

plying the band must be such as will not crush or injure the cigar.

The foregoing are generally some of the objects of my invention which are accomplished by the machine which is the subject 55 of this application.

A further object of my invention is the provision of means for gumming the band after it is removed from the pile of bands.

A further object of my invention is to provide means so that the gumming mechanism will be rendered ineffectual unless a band is in position to receive gum or adhesive. 60

A further object of my invention is the provision of means for utilizing unguammed bands and applying gum or adhesive thereto. I have found that when gummed bands are used for banding cigars, that the bands have a tendency to adhere or stick or cake together, with the result that the operator 70 must break the adhesion. This is usually accomplished by the operator taking a pile of bands and fanning the gummed end, and in this manner, break the adhesion. In many instances the bands, nevertheless, adhere together and two or more bands will consequently be removed from the pile of bands. I have found that by using unguammed bands this difficulty is overcome, and it is not necessary for the operator to fan the bands and 75 that they will not adhere. Unguammed bands effect a great saving in the manufacture in that the gumming operation is very difficult and complicated, requiring a great deal of labor. It has also been found that great difficulty is eliminated in handling unguammed bands and that a greater number of bands can be placed in the band magazine as both sides of the band are of the same thickness and hence the pile of bands on both 80 ends is of the same level, which is not so when using gummed bands. 85

A further object of my invention is to provide improved means for separating the bands. 90

Another object of my invention is to provide a single means for separating and removing a band from the stack or pile of bands.

A further object of my invention is to con- 100

struct a cigar banding machine having a single means, for separating and moving in a single cycle of operation, a band from a band magazine to a position where an adhesive or moisture is applied and thence to a banding position where the band is applied to a cigar.

Other objects and advantages will appear as the nature of the improvements is better understood, the invention consisting substantially in the novel arrangement and correlation of instrumentalities herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive, standpoint.

The inventive idea involved is capable of receiving a variety of mechanical expressions, one of which, for the purposes of illustrations, is shown in the accompanying drawings, in which—

Fig. 1 is a rear elevation of my improved banding machine embodying my invention;

Fig. 2 is a partial front elevation of the upper portion of my machine showing some of the essential operating mechanism; the hopper being partly broken away and the discharge table portion also being partly broken away;

Fig. 3 is a plan view of the same;

Fig. 4 is a side elevation of the upper portion of my machine viewed from the left hand side of Fig. 2;

Fig. 5 is a side elevation of the same viewed from the right hand side of Fig. 2;

Fig. 6 is a plan view showing a portion of the driving mechanism;

Figs. 7, 8, 9 and 10 are detailed views illustrating the various steps during the cycle of movement necessary for the moistening of the tape and for applying gum to the band;

Figs. 11, 12, 13, 14, 15, 16, 17 and 18 are detailed views illustrating the various steps during the cycle of movement necessary for wrapping the band around the cigar and for discharging the banded cigar;

Fig. 19 is a full size detailed view; partly in section showing a portion of the band magazine, tension device, the crimping device, and a portion partly in section of the band separator and conveyor;

Fig. 20 is a full size end view, partly in section, taken on the line 20—20 of Fig. 19;

Fig. 21 is a full size detailed view illustrating a portion of the band magazine and the suction end of the band separator and

conveyor in section in its lowered position;

Fig. 22 is a detailed view of the same illustrating the band separator and conveyor in section in its raised position, with the air exhausted, showing the lowermost band separated from the pile of bands;

Fig. 23 is a full size partial plan view of the suction end of the band separator and conveyor;

Figs. 24, 25, 26, 27, 28 and 29 are full size detailed views of the separator and conveyor, illustrating the various steps during the cycle of movement necessary for removing the lowermost band and conveying it to the adhesive position and thence to the banding position;

Fig. 30 is a detailed view showing the cam and rocker arm for actuating the band separator and conveyor;

Fig. 31 is a vertical sectional view of the exhaust valve;

Fig. 32 is a horizontal sectional view of the exhaust valve taken on the line 32—32 of Fig. 31;

Fig. 33 is a detailed view of the exhaust valve cap.

Referring to the drawings, the machine comprises a frame A, a table B on which is located a row feed hopper D at the right, and a box supporting shelf M at the left (Fig. 1).

The operator seated in front of the machine removes the cigars from a box. Said cigars, when removed, are not disturbed from the position which they occupied in the box. As a result of the packing, the cigars assume various irregular shapes in cross-section. The removal of these cigars is accomplished by means of a tape or band and are taken by the operator and lowered into the row feed hopper D, which feeds the rows or layers starting from the bottom row, out upon the table B.

I will now give a more detailed description of the operating mechanism:

Driving mechanism

A motor 1 is mounted on a motor supporting base 2, pivoted at 3 on the rear of frame A, carries two pulleys, 4 and 5 respectively, on each end of its armature shaft. The pulley 4 by means of belt 6 drives the pulley 7, secured to a pump shaft 8, mounted in suitable bearing 9, 9 in frame A. Mounted on pump shaft 8, within frame A is an exhaust pump 10.

The pulley 5 by means of belt 11, drives pulley 12 secured to worm drive shaft 13, mounted in suitable bearings 14, 14 in frame A. Secured to the free end of shaft 13 is a worm 15, meshing with a worm gear 16 mounted to rotate on a main cam shaft 17. (Figs. 2, 3 and 6).

Integral with one side of the worm gear 16 are the cams 18 and 19, on the opposite side of which is securely fastened the female

clutch plate 20, all of which run continuously. The cams 18 and 19 operate the gum applying mechanism J, while the female clutch plate 20, when engaged by the clutch dog 21 carried 5 in the clutch 22 securely fastened upon the main cam shaft 17, drives said shaft, causing the entire mechanism to operate.

The worm gear 16, cams 18 and 19, and female clutch plate 20, will hereinafter be 10 referred to as the worm-gear-clutch-unit C.

Secured to main cam shaft 17 is a mitre gear 25, meshing with mitre gear 26, secured on a cross cam shaft 27, mounted in suitable bearings 28-28 in frame A. Also secured 15 to the cross cam shaft 27 is a spur gear 29, meshing with a spur gear 30, secured on a cross cam shaft 31, mounted in suitable bearings 32-32 in frame A.

When the clutch dog 21 of clutch 22 is released it engages the clutch plate 20, of the continuously driven worm-gear-clutch-unit C, thereby causing main cam shaft 17 and cross cam shafts 27 and 31 to make one cycle of operation. At the completion of the cycle 25 the clutch dog 21 is withdrawn in the usual manner, allowing the worm-gear-clutch-unit C to keep the gum applying mechanism J in operation, when the rest of the machine is not in operation.

Exhaust valve

Mounted within the frame A on motor driven shaft 8 is a rotary exhaust pump 10 of the ordinary type, having intake and discharge ports. A pipe 33 connects the intake port and a cap 34 fastened to the valve body 35, secured on the side of frame A. Slidably mounted within the valve 35 is a vertically moving valve stem 36, to the lower end of 35 which is attached a spring 37. The other end of spring 37 is attached to a spring post 38, secured in the frame A, said spring 37 holding valve stem 36 in its lowermost position. The upper end of said valve stem 36 is pivotally connected by a link 39 to a bell crank 40, pivotally mounted on the stud 41. The free end 42 of bell crank 40 carries a cam roller 43, actuated by cam 44, secured on main cam shaft 17. The extreme free end 45 of bell crank 40 extends around the side of frame A, the purpose of which is more fully described hereinafter.

The valve cap 34 attached to pipe connection 33 forms an L, and has an elongated opening at its flanged end corresponding to a vertical slot 46, in the valve body 35.

A hole 47 drilled into one side of valve stem 36 travels within the limits of the vertical slot 46, (see Figs. 31 and 32) while a hole 60 48 drilled at a right angle to hole 47, and connecting therewith registers alternately with two holes 49 and 50, in valve body 35, said holes 49 and 50 having screwed therein the hose nozzles or nipples 51 and 52. A flexible 65 tube 53, attached to the hose nozzle 51, leads

to the banding mechanism K, while the flexible tube 54, attached to hose nozzle 52, leads to a formed connection 55, to which is attached two flexible tubes 56 and 57. The flexible tube 56 leads to the band separator and conveyor F, while the flexible tube 57 leads to the emergency gum control H, hereinafter explained.

In order that the band held by the exhaust to either the band applying mechanism K or on the band separator and conveyor F, may be instantly released when the exhaust is cut off by the action of valve stem 36, there are two small holes 58 and 59, drilled in and through valve stem 36. When valve stem 36 is raised cutting off the exhaust at hose nozzle 52, or on the band separator and conveyor F, and the emergency gum control H, the small hole 58 in valve stem registers with a small hole 60 drilled in valve body 35, allowing air to enter, thereby breaking the vacuum between the valve stem and the band held on the combined band separator F. With the valve stem in this position the exhaust is on the banding mechanism K. When the valve stem 36 is lowered, cutting off exhaust on banding mechanism K, the small hole 59 in valve stem 36 registers with a small hole 61 as illustrated in Fig. 31, allowing air to enter, thus breaking the vacuum between the valve 95 stem 36 and the banding mechanism K.

Emergency-gum-control

The object of this device is to cause the adhesive mechanism not to function unless a 100 band is in position ready to receive the adhesive, preventing gum from being applied to the band cushion or support.

The emergency gum control comprises a bracket 62 (Fig. 5) having a vertically disposed cylinder 63, enclosing a vertically moving piston 64. A spring 65 keeps the piston 64 in its upward position. The flexible tube 57, connects the cylinder 63 with valve nozzle 52 by means of the forked member 55. The upper end of piston 64 is pivotally connected to bell crank 66, pivotally mounted on stud 67, secured in bracket 62. The free or upright end 68 of bell crank 66 is so positioned that in its normal or effective position it will check the downward movement of the swinging band cushion 69, of the gum applying mechanism J, preventing the said band cushion 69 from reaching its extreme downward or effective position, unless there is a band covering or closing the suction holes 70 of the band separator and conveyor F, in the following manner:

With the machine in its normal or stop position the band separator and conveyor F is 125 in its lowered or horizontal position, as shown in Fig. 24, the suction holes 70 below the stack of bands 71 with the exhaust cut off, the free or upright end 68 of the bell crank 66, in its normal or effective position, checking the 130

downward movement of the band cushion 69, preventing it reaching its effective or gum applying position. As the machine starts its cycle of operation, the band separator and conveyor F swings up against the lowermost band of the stack of bands 71, as shown in Fig. 25, closing the suction holes 70. The valve stem 36 is lowered, exhausting the air from the combined band separator and conveyor F, and flexible tubes 56 and 57, creating a vacuum in cylinder 63, drawing down piston 64 against the action of the spring 65, rocking the bell crank 66 and swinging the free or upright end 68 out of the path of the downward swinging band cushion 69, which is still in its upward position. The band separator and conveyor F now swings downward to its horizontal or conveying position as shown in Fig. 26, and starts its rearward movement to the gum applying position. The band cushion 69 is lowered to its effective or gum applying position which is directly over the end of the band 71 to be gummed, and when in this position, the gum is applied. (See Figs. 8, 9 and 27). The band separator and conveyor F now moves forward, bringing the band 71 directly beneath the hollow stem 72 of the banding mechanism K as shown in Fig. 28, the band cushion 69 having moved to its upward position. At this time the valve stem 36 is raised cutting off the exhaust and breaking the vacuum in the band separator and conveyor F and the cylinder 63, the spring 65 forcing the piston 64 upward, rocking the bell-crank 66, bringing the free upright end 68 back to its effective position where it will continue to check the downward movement of the continually operating band cushion 69 until the band separator and conveyor F again moves up against the lowermost band of the stack of bands 71 on the next cycle of operation of the entire machine.

The purpose of the emergency gum control is to prevent the moistened gum from reaching the band cushion 69, which moves down over the end of the band held on the band separator and conveyor F to form a cushion against which the end of the band is supported while the gum is applied as already described herein. If there were no band on the band separator and conveyor F, and the band cushion 69 was allowed to reach its effective position, the gum would be applied thereto causing the following bands to adhere to said band cushion 69, thereby causing improper delivery to the banding mechanism K. If the band separator and conveyor F moves away from the stack of bands 71, failing to draw down a band, leaving the suction holes 70 of band separator and conveyor F open, the vacuum is broken in cylinder 63, allowing upright end 68 of bell crank 66 to return to its effective position in time to check the downward movement of the band cushion 69.

The suction holes 70 in the band separator and conveyor are large enough to weaken the vacuum when all the suction holes 70 are left open or uncovered, but a poorly adjusted band magazine, or a defective or torn band may cause the band separator and conveyor to draw a band down part way, or draw down one of its ends, in which case one or more of the suction holes 70 may be left open or uncovered. This would cause a slower breaking of the vacuum in cylinder 63, thereby delaying the free upright end 68 of bell crank 66 in reaching its normal or effective position in time to stop the downward movement of the band cushion 69. Therefore, in order to insure the quick return of the upright end 68 of bell crank 66 to its effective position when the suction holes 70 of band separator and conveyor F are not completely closed or covered, the cam 44 controlling the valve stem 36 is so designed to raise the valve stem 36, thus reducing the vacuum about 80%. This reduction of vacuum takes place after the band separator and conveyor F has been returned to its horizontal or conveying position, it being remembered however, that the free or upright end 68 of the bell-crank 66 has been swung out of the path of the downward moving band cushion 69 at the time the suction holes 70 of band separator and conveyor F are closed or covered by pressing against the lowermost band of the stack of bands 71, at which time the valve stem 36 is lowered, exhausting the air in the combined band separator and conveyor F, creating a vacuum in cylinder 63.

Band check

In order that the operator may check or stop the feeding of the bands, a bell-crank 74 is pivotally mounted on a stud 75 of a bracket 76 secured to the top surface of table B. A spring 77, one end of which is attached to the downward extending arm 78 of bell crank 74, and the other end to a spring post 79, secured to the under side of table B tends to hold the downward extending arm 78 of bell crank 74 in its ineffective position. This position being limited or fixed by a stop pin 80, also secured in the table B.

The free end of the bell crank 74, which is above the table B, extends toward the front of machine and terminates in a key 81, which, when pressed down by the operator, rocks the bell crank 74, swinging the downwardly extending arm 78 into its effective position, which is directly over, and in the path of the extreme end 45 of the bell crank 40, operating the valve stem 36. The proper time for the operator to press down the key 81 to stop a band from feeding is just before tripping the foot treadle (not shown) when starting the machine on its cycle of operation. At this time the valve stem 36 is in its raised position, or the extreme end 45 of bell crank 130

40 being in its lowered position. As the key 81 is pressed down, the downwardly extending arm 78 of bell crank 74 moves over the extreme end 45 of bell crank 40, thereby checking its movement which will prevent the valve stem 36 from moving downward, thus preventing a vacuum from being created in the band separator and conveyor F and the cylinder 63.

10 When the operator is ready to feed cigars to the banding position beneath banding mechanism K, operator trips foot treadle (not shown), which releases the clutch 22 and starts the machine on its cycle of operation. As the operator feeds each cigar into the banding position, the treadle must be tripped unless said operator is capable of feeding at the speed of which the machine is operating. In this case a continuous pressure is kept on the foot treadle, only relieving said pressure when feeding is to be discontinued. Before feeding is discontinued, however, the operator must first press down the key 81 when the last cigar is placed in the 25 banding position which prevents the band separator and conveyor from removing a band from band stack 71. If a band was fed in this case the gum would become dry and the band wasted.

30 *Band magazine*

The band magazine comprises two vertically disposed uprights or end supporting members 83 and 84, secured to the brackets 35 85 and 86, respectively, which are slidably mounted on a bar 87, secured in the frame A, while their lower ends 88 straddle the bar 89, secured to the frame A for the purpose of perfect alignment. Then brackets 85 and 86, 40 and uprights 83 and 84 are adjustable toward and away from each other by means of a right and left hand threaded screw 90, in order to take care of the various lengths of bands. Each of said uprights 83 and 84 carry a pair of pivoted side guide rods 91—91 and 92—92, respectively, which are adjustable toward and away from each other by means of a right and left hand threaded screws 93, to take care of bands of various 45 widths. Driven in the base of these uprights 83 and 84 are supporting pins 94, which support the stack of bands 71. (See Fig. 19.) The upright 84 has a spring pressed tension member 95, pivoted at 96, the free upright 50 end 97 of which extends from a slot or groove 98 in said upright. The other free end 99 extends outward through the base of upright 84 and then downward, and terminates in an outward extending end 100, which is under 55 and in the path of movement of a pin 101, extending from a crimper lever 102, said outward extending end 100 having fastened thereon a key plate 103, the purpose of which is more fully described hereinafter.

60 The tension member 95 applies an end pres-

sure against the end of the stack of bands 71, this pressure being momentarily relieved in the following manner:

Consider the machine being in its normal or stop position and the magazine having been adjusted to the size of the band to be used. The operator then presses down on the key 103 which moves the upward extending end 97 of the tension member 95 backward into the slot 98, and then proceeds to fill 70 the magazine with bands, relieving the pressure on the key 103 when the stack of bands have reached a point above said upward extending end 97.

The machine is then started on its cycle of 80 operation. The band separator and conveyor F swings upward against the lowermost band, raising the stack as illustrated in Fig. 25, and as said band separator and conveyor F swings downward, the bands below the upward extending member 97 follow it downward until they rest on the supporting pins 94, while the bands under tension, due to the end pressure exerted upon them by the upward extending member 97, are held up. This allows only the weight of the lower part of 85 band stack to rest on the supporting pins 84 as the band separator F continues down, drawing the ends of the lowermost band out 90 from under the stack of bands and away from the supporting pins 94. On reaching its conveying position, the band separator and conveyor moves rearward to the gumming and crimping position. As the crimping lever 102 rocks to crisp the band, the pin 101, extending from crimpler lever 102, presses down on the key end 100 of tension member 95, withdrawing the upward extending end 97 of tension member 95, thus relieving the 95 tension and allowing the upper portion of the stack of bands 71 to join the lower portion. The return of the crimpler lever 102 to its normal position allows the tension member 95 to again exert an end pressure to the stack of bands 71. This operation is repeated during 100 each cycle of operation.

Combined band separator and conveyor F

Secured to the frame A is a bracket 104 having a raceway 105 and a slide 107 reciprocating in said raceway and being held in position by the jibs 106. Secured to the underside of slide 107 is a rack 108, meshing with a spur gear 109 which is secured on rocker shaft 110 mounted in suitable bearings in the bracket 104. Fastened to the outer end of the rocker shaft 110 is a pinion gear 111 meshing with a segment bell crank 112, pivoted at 113 on the stud 114 which is adjustably held in the frame A. The free end 115 of the segment bell crank 112 carries a cam roller 116, actuated by a cam 117 pinned on the cross cam shaft 27 mounted in suitable bearings 28 in the frame A. Said cross cam shaft 27 also carries a mitre gear 26 meshing with a mitre 120

125

130

gear 25 fastened on the main cam shaft 17. The cam 117 is so profiled as to give an intermittent reciprocating movement to the slide 107 as will hereinafter be described.

5 Mounted on the upper side of the slide 107 is a bracket 118 on which is pivotally fastened at 119, one of the parts 120 comprising the band separator and conveyor F which has fastened to its free end an extension 121 in 10 the end of which are located three suction holes 70, same being located in the slightly depressed or concaved surfaces 122, running in the direction of its length. The three suction holes 70 are connected by air passages 15 123, which extend lengthwise through extension, joining air passages 124 running lengthwise through the member 120 and terminating in a hose nozzle 125 extending from side of said member 120. A flexible tube 56 connects the hose nozzle 125 with the forked connection 55, which leads to the valve nozzle 52.

In order to keep the band separator and conveyor F in perfect alignment, a keel 126, 25 held in the bracket 118, extends upward through a slot 127 in the member 120.

The combined band separator and conveyor F 120 also has a swinging movement, that is, from its horizontal or conveying position 30 upward and return, which is brought about in the following manner:

When the machine is in its normal or stop position, a lug 128 extending from the member 120 and carrying a hardened plate 129, is 35 directly above a roller 130 on a stud 131, which is carried by an arm 132 pivotally mounted on a stud 133, fastened in the bracket 104. The free end of the arm 132 carries a roller 134 which is engaged by the free end 40 135 of a bell-crank lever 136 pivotally mounted on a stud shaft 137, secured in the frame A. The other end of bell crank 136 carries a cam roller 138, actuated by a cam 139 fixed on the cross cam shaft 31. (See Fig. 30.) Said 45 cam 139 is so profiled as to rock bell-crank 136, raising the arm 132, which in turn raises and lowers the band separator and conveyor F when it is in a position with the suction holes 70 in line with the stack of bands 71.

50 With the machine in its normal or stop position the suction holes 70 in the extension member 121 of the band separator and conveyor F are directly beneath the stack of bands 71. The machine starts its cycle of 55 operation through the action of the cam 139. The bell crank 136 raises the arm 132 which swings the band separator and conveyor F upward against the lowermost band of the stack of bands 71, raising the stack slightly. The valve stem 36 is lowered causing a suction to be created at the holes 70 of the extension member 121 which draws portions of the lowermost band down into the depressed or concaved surfaces 122 (see Fig. 22) thereby causing a vacuum to be built up in

the flexible tubes 56 and 57, thereby actuating the piston 64 as already described herein. Having thus separated the lowermost band from the next one above, the combined band separator and conveyor F swings downward 70 to its conveying position, thereby drawing the ends of the lowermost band away from the supporting pins 94, allowing the lower portion of the stack of bands 71 to rest upon said supporting pins. By means of the cam 117 75 pinned on the cross cam shaft 27 (see Fig. 4) the bell crank 112, the pinion gear 111, the gear 109 and the rack 108, the band separator and conveyor F is caused to move rearward to the gumming and crimping position, where 80 it rests while the crimping device closes and grips one end of band while the gum is being applied to the other end. When this action is taking place the pressure of the tension member 95 upon the ends of the upper portion of the stack of bands 71 has been relieved as already described herein. After 85 the gum has been applied, the crimping device opens freeing the band and at the same time making the tension member 95 effective 90 again as already described herein. The band separator and conveyor F, due to the action of the cam 117, then moves forward toward the banding mechanism K, and stops when the band is directly beneath the hollow stem 95 72 of said banding mechanism (see Figs. 28 and 29). During the brief rest in this position the valve stem 36 is raised, breaking the vacuum in band separator and conveyor F, thus freeing the band and creating a 100 suction in the hollow stem 72 of banding mechanism K which removes said band from the band separator and conveyor F, said hollow stem 72 staying in this position and holding the band while band separator and conveyor F moves rearward to its normal or stop position with the suction holes 70 again directly below the stack of bands 71, which completes the cycle of operation. 105

Crimping mechanism

Secured on an extending lug 140 of the band magazine supporting bracket 86 is the upper or female crimping member 141 and mounted on a stud 142 is the rocker arm 102 115 upon one end of which is fastened the lower or male crimping member 143. The other end of rocker arm 102 is connected to a connecting rod 144; the lower end of which is connected to the free end of a bell crank 145 120 mounted on a frame stud 146. The free end of the bell crank 145 carries a cam roller 147 actuated by a cam 148, secured on the main cam shaft 17. As the band separator and conveyor F delivers the band to the gum applying position, the tail of the band is in line with the crimping mechanism, said end of the band resting just below the upper or female crimping member 141. The cam 148 125 actuating the rocker arm 102 causes the 130

lower or male crimping member 143 to mesh with the upper or female crimping member 141, gripping the end of the band between them and crimping it, which greatly assists in overlapping the ends by the banding mechanism K owing to the irregular shapes of the cigars to be banded.

When the crimping members 141 and 143 mesh they also hold the band while the gum 10 is applied, after which the lower or male crimping member 143 is swung downward by means of a spring 149 and the cam 148 and the band is moved by band separator and conveyor F toward the banding mechanism 15 K. The spring 149 is attached to the bell-crank 145 and a spring post 150 secured in the frame A.

Foot control

20 Pivotedly mounted on a stud, at the base of frame A, is a foot treadle not shown in the drawings, which is held in its raised position by spring attached to it, and a spring post secured in the frame A. The treadle 25 is connected by a link with a clutch control arm 156 pivotally mounted on a frame stud 157. The clutch control arm 156 is held in its upward position by a spring 158 (see Figs. 2 and 6), attached to a spring post 159 in 30 the frame A, the free end of said clutch control arm 156 being wedge shaped and resting in the groove 22' of the clutch drum 22, fastened on the main cam shaft 17.

With the machine in its normal or stop 35 position, the clutch control arm 156 is in its raised or upward position. As operator trips foot treadle, the clutch control arm 156 is drawn down freeing the spring pressed clutch dog 21 of the clutch 22 which engages the female clutch plate 20, thus starting 40 the machine on its cycle of operation.

As the operator relieves the pressure on 45 foot treadle, the clutch control arm 156 returns to its normal or raised position by the spring 158 where, at the completion of the cycle it withdraws the clutch dog 21, rendering the clutch ineffective.

Banding mechanism K

50 Mounted to a slide in suitable bearings 160, 161, in the frame A (Figs. 2 and 4) is a vertical shaft 162, having secured on its extreme upper end a frame or bracket 163, to which is pivoted at 164 a connecting rod 165; 55 the lower end of which is pivotally connected to a cam lever 166 mounted on a frame stud 167. The cam lever 166 carries a cam roller 168 which is actuated by a cam 169 secured on the cross cam shaft 27 driven by 60 the main cam shaft 17 through the mitre gears 25 and 26. The cam 169 is so profiled to impart an intermittent vertical reciprocating movement to the vertical shaft 162, or the banding mechanism K with the aid of a 65 spring 170, one end of which is attached to a

stud 171 in the frame or bracket 163; the other end being attached to a spring post 172 carried by the free end of the segment bell-crank 112. Secured on the vertical shaft 162, between the bearings 160 and 161, is an 70 arm 173; the free end of which straddles the member 174 fastened on the frame A for the purpose of alignment. Held in suitable bearings 175 and 176 of the frame or bracket 163 is the vertical hollow stem 72 carrying 75 a platen 177 on its lower end. The upper end of said hollow stem is threaded for the purpose of adjustment by means of the nuts 178 and 179, said end terminating in a hose nozzle 180 to which is attached a flexible tube 80 181; the other end of which is attached to the hose nozzle 182 of the vertical shaft 162 (see Figs. 1, 2, 3 and 4) having an air passage through its entire length, to the lower end of which is attached a flexible tube 85 183 connecting with the hose nozzle 51 of the valve body 35 by means of which the air to be exhausted from hollow stem 72, as will hereinafter be explained.

Referring more in particular to Figs. 2, 90 11, 12, 13, 14, 15, 16, 17 and 18, it will be seen that a spring 185 enclosing the hollow stem 72 between the shoulder 186 of the hollow stem 72 and the bearing 175 tends to keep the hollow stem 72 in its lowered position. The hollow stem 72 is raised against the tension of the spring 185 when the platen 177 comes in contact with the cigar as the vertical shaft 162 is moved downward. Mounted on the studs 187 and 188 secured in frame 100 or bracket 163 are the rocking folder arms 189 and 190, respectively, each of which carry a pivotally mounted folding finger 191, held in their normal positions by leaf springs 192, which exert a pressure against the upward 105 extending members 193, said members resting against the inner side of arms 189 and 190. Each of the fingers 191 carries a small roller 194, at its free end, and a roller 195 on its pivoting pins 196. The platen 177 is slotted 110 to receive the end of the folding tapes 197, said tapes passing under the fingers 191 and around the rollers 195, their ends being attached to the hooked ends of the springs 198, which in turn are attached to the spring 115 posts 199 secured in the upper ends of rocking folder arms 189 and 190, said springs 198 causing the folder tapes 197 to be held under tension. The upward extending end 200 of rocking arm 190 is connected to a link 201, the other end of said link being connected to a bell crank 202 mounted on a stud 203 in the frame or bracket 163. Pivotally connected to one end of the bell crank 202 is a downwardly extending connecting link 204, (see 120 Fig. 4) its lower end having a slot 205. The length of said slot 205 corresponds to the vertical movement of the vertical shaft 162. A stud 206 connects the slotted end of the connecting link 204 to the end of a cam lever 207 125

mounted on a frame stud 208 (see Fig. 6). The end 209 of the cam lever 207 carries a cam roller 210 which is actuated by a cam 211 secured on the main cam shaft 17. A spring 212, one end of which is attached to a spring post 213 carried by the cam lever 207, and having its other end attached to spring post 214; fixed in the frame A, tends to keep said cam lever 207 in its lowered position by 5 means of which through the connecting link 204, the bell crank 202 and the link 201, the rocking folder arm 190 is held in its open position, said open position being limited by the upper end 200 of the rocking folder arm 190 10 coming in contact with the stop 215 secured in the upper bearing 175 of the frame or bracket 163. It is therefore easily seen that the action of the cam 211 causes the lower end of the rocking folder arm 190 carrying 15 the folding finger 191 to move toward the hollow stem 72 or to its closed position.

The rocking folder arm 189 has a downward extending finger 216 which rests against a roller 217 carried on the upper end 218 of 20 a cam lever 219 which is pivoted on a frame stud 220. The lower end 221 of the cam lever 219 carries a cam roller 222 actuated by a barrel cam 223, secured on cross cam shaft 31 (see Fig. 6). A spring 224 attached to 25 a spring post 225 of rocking arm 189, and also attached to a spring post 226 secured in the frame or bracket 162 causes rocking folder arm 189 to move toward hollow stem 72, or its closed position; as the cam roller 30 222 follows the profile of the barrel cam 223; said rocking folder arm 189 being moved away from hollow stem 72 to its open position by the closing of the rocking arm 190 which actuates a pivotally mounted swivel member 35 227 carried at the upper end 228 of said rocking folder arm 189, said swivel member being slidably mounted in the elongated opening 229 in the link 201. As the rocking folder arm 190 reaches its closed position, the rocking folder arm 189 reaches its open position, the barrel cam 223 being so profiled and timed 40 as to cause the roller 217 of cam lever 219 to move toward the downward extending finger 216 and hold the rocking folder arm 189 in its 45 open position during the rest of the cycle of operation; the rocking folder arm 190 moving back to its open position by means of the springs 230, 212 and the cam 211. An adjustment is provided by means of the upper end 50 228 of rocking folder arm 189 having a slot 231 through which bolt 232 passes, securing said upper end 228 to an upward extending lug 233 of the rocking folder arm 189. The operation of the banding mechanism K is 55 as follows:

Toward the completion of the cycle of operation, the band separator and conveyor F, carrying a gummed band, is moved forward toward the banding mechanism K. As the banding mechanism reaches its raised

position, the band separator and conveyor F brings the band directly under the hollow stem 72 and the folder tapes 197; where it rests while the valve stem 36 is raised, thereby breaking the vacuum in the band separator and conveyor F. At the same time the air is exhausted from the hollow stem 72, thereby transferring the band from the band separator and conveyor F to the platen 177 of the banding mechanism K (see Figs. 28 70 and 29). The band separator and conveyor F then moves away, leaving the machine in its normal or stop position. The operator then feeds a cigar into the gauged banding position and trips foot treadle, thereby starting machine on its cycle of operation 75 (see Fig. 24). The hollow stem 72, by means of the vertical shaft 162, moves downward until the band rests on the cigar, compressing the spring 185 as the folding mechanism 80 K continues down to its lowermost position (see Figs. 12, 13 and 25). The retarding of the downward movement of the hollow stem 72 by the cigar, together with the folder tapes 197, the ends of which are attached to 85 the platen 177 of the hollow stem 72, has wrapped the band around the top and both sides of the cigar, leaving both ends of said band extending downward and directly in the path of folding tapes 197 and the folding 90 fingers 191. The rocking folder arm 189 then moves to its closed position, the folding finger 191 carrying the folding tape 197 and the ungummed end of band around the underside of cigar. The rocking folder arm 95 190 now moves toward its closed position carrying the folder tape 197 and the gummed end of band around and over the ungummed end, thereby moving the rocking folder arm 100 189 to its open position. The action of the barrel cam 223 upon the cam lever 219, holds the rocking folder arm 189 in its open position. The rocking folder arm 190 now moves toward its open position. During this movement the member 234 forming the lower gripping 105 jaws is raised, bringing the rubber finger 235 into contact with and exerting a yielding pressure on the overlapping ends of the band. At the same time the upper gripping fingers 236 and 237 are lowered as the rocking folder arm 190 reaches its open position. (See Fig. 16.) The banding mechanism K 110 is then raised and the discharged mechanism L moving to its extreme right hand position carrying the banded cigar along with it to the normal or stop position of the discharge mechanism (see Figs. 17 and 18).

Gauge mechanism

In order that the band will be properly centered on the cigar so that the crest, trademark or medallion will be in line with the longitudinal axis thereof, a side gauge is employed as well as a centering device for the head of the cigar. The centering device con- 120 125 130

sists of a V shaped member 238 secured to a rod 239 which is slidably mounted in the bearings 240 and 241 mounted on the jibs 106, fastened on the bracket 104, secured to the frame A, said rod 239 passing through the bracket 118 fixed on the slide 107 (see Fig. 4). The rod 239 also passes through an adjusting member 242 having a pivoted catch 243 which engages one of the series of notches 243; said notches determining the position of the band from the head of the cigar. The adjusting member 242 rests and travels on the jibs 106, being moved forward or toward the banding mechanism K by the action of bracket 118 on the forward movement of the band separator and conveyor F. As the adjusting member 242 reaches its forward position, the arm 244 pivoted on a bracket stud 245 moves in behind the extending end 246 of the adjusting block 242 due to the action of the leaf spring 247 fastened on the side of bracket 104. The adjusting block 242 is held in this position while the band separator and conveyor F returns to its normal or stop position. The pivoted arm 244 is so shaped at 248 that a pin 249, secured in bracket 118, will move said arm 244 from behind the adjusting block 242 during the later part of the rearward movement of the band separator and conveyor F. After the arm 244 has been swung out from behind the adjusting block 242 a strip 250 having its end 251 bent at right angles is engaged by the rear of the bracket 118 of the band separator and conveyor F, which draws the adjusting block 242 and the rod 239 attached to the V shaped member 238, back, or away from the head of the cigar, so that said V shaped member 238 will not interfere with the removal of the cigar by the discharging mechanism L.

Side gauge

As the operator feeds the head of cigar into the V shaped member 238, said cigar moves sideways toward the right until it presses against a side gauging member 252, adjustably mounted on a bar 253 by means of a slot 254 and a thumb nut 255, the bar 253 being pivotally mounted in a guide member 256 secured to the underside of the table B. The gauging member 252 is adjustable sideways so that the longitudinal axis of the cigar will correspond with the center line of the banding mechanism K. A spring 257 nested in the frame A, and pressing upward against the underside of the bar 253 tends to keep bar 253 in its effective or upward position; this position being fixed by the upper side of said bar 253 coming in contact with the guide member 256. The member 252 has an upward extending finger 252' which is adjustable toward and away from the center line of the banding mechanism K. This upward extending finger 252' extends through an opening 258 in the table B, which is its ef-

fective position. The free end of the bar 253 carries a cam roller 259 which is engaged by a wedge shaped cam 260, secured on a frame 261 of the discharge mechanism L. As the discharge mechanism L moves toward the cigar held in position against the finger 252', the wedge shaped member 260 comes in contact with the roller 259, swinging the finger 252' below the upper surface of the table B, so that the banded cigar gripped by the discharge mechanism L may be removed sideways from the gauged banding position. After the discharge mechanism L carries the cigar clear of 252', its continued movement allows the finger 252' to swing upward to its effective position.

Gum applying mechanism

The gum applying mechanism is continuously driven by the worm-gear-clutch-unit which operates at the maximum speed of the machine, while the number of the banding operations per minute depends upon the speed of the operator. For instance, the maximum speed of the worm-gear-clutch-unit and gum applying mechanism J driven by it, is 65 cigars per minute, but the banding operation is controlled by the feeding speed of the operator. If the operator is capable of feeding at the rate of 65 cigars per minute, a continuous pressure is applied to the foot treadle which allows the entire machine to operate in unison with the worm-gear-clutch-unit. The gum applying device consists of a continuous strip of gummed paper 263, receiving moisture from a water pot 264, by means of a brush 265, said gummed strip advancing step by step with each operation of the worm-gear-clutch-unit; due to this method of operation, the consistency of the gum to be applied to the bands is the same, regardless of the speed of the operator. For example, the banding operation may be stopped for one hour and as long as the worm-gear-clutch unit is kept in operation, the consistency of the gum will be the same when the operator again starts the banding operation. This is very important where one operator is employed, because the banding operation must be discontinued while the layers or rows of cigars are returned to the box. As explained under "driving mechanism" the worm-clutch-unit is mounted to rotate continuously on the main cam shaft 17. Mounted in suitable bearings 266 and 267 on the frame A is a rocker shaft 268, secured to one end of which is a cam lever 269 carrying a cam roller 270 actuated by the cam 18 of the worm-gear-clutch-unit, said roller 270 being held in constant rolling contact with said cam 18 by the spring 268a. On the opposite end of the rocker shaft 268 is fastened the arm 271 which is pivotally connected to the lower end of connecting rod 272, the upper end of which is pivotally connected to the arm 273 of a bell crank 274 mounted

on a stud 275 secured in band magazine supporting bracket 85.

The upward extending arm 276 of the bell crank 274 carries a stud 277 on which is mounted a water reservoir 264, which is also supported from beneath by a raising device which is more fully described hereinafter. The cam 18 of the worm-gear-clutch-unit is so profiled as to give an intermittent reciprocating movement to the reservoir 264, toward and away from the band held on the band separator and conveyor F.

Mounted on the free end of water reservoir 264 is the member 278 under which the gummed strip 263 passes being guided by the two downward extending flanges or guides 279, the extreme end of said member 278 being rounded at 280. The upper surface of the member 278 forms a support for the gummed strip 263, having two upward extending flanges 281, between which said gummed strip 263 passes. These upward extending flanges 281 have open slots 282 between them in which rests the tension weight 283 under which the gummed strip 263 passes. Just above the reservoir 264, and secured to the magazine supporting bracket 85, is a guide and clamp bracket 284 having a recess 285 extending in direction of its length, the end of said bracket 286 being curved downward, the purpose of which is more fully described hereinafter. Pivoted on a stud 287, fixed in the bracket 284, is a clamping arm 288, the end of which carries a hardened beveled clamping member 289, which, when the clamping arm is lowered, engages a hardened member 290, fastened in bracket 284 and located within the recess 285. The clamping arm 288 is held in its lowered or effective position by spring 291 attached to spring post 292, fixed in the magazine supporting bracket 85. The clamping arm 288 is raised to its upward position by a tappet 293, one end of which is located in a socket 294, and bears against the adjusting screw 295 of the clamping arm 288. The purpose of the adjusting screw is to regulate the consistency of the gum, by increasing or decreasing the travel of the gummed strip 263 on each cycle of operation. The gummed strip 263 is advanced by the forward movement of water reservoir 264 toward the band separator and conveyor F, while the discharge end of gummed strip is held by clamping arm 288. The shortening of the clamping time of the arm 288 will shorten the travel of gum strip 263, this shortening of time being effected by lowering the adjusting screw 295 so that the tappet 293 will engage it sooner. The lower end of the tappet 293 is pivotally connected to an arm 296 of a bell crank 297, mounted to rock freely on the rocker shaft 268 (see Fig. 6). One end of the bell crank 297 carries a cam roller 298 actuated by the cam 19 of the continuously rotating worm-gear-

clutch-unit. The arm 296 of the bell crank 297 also carries a second tappet 299, pivoted on a stud 300, the end of said tappet 299 being located in a socket 301 in the water reservoir raising arm 302, said arm 302 being pivoted on a stud 303 fixed in the magazine supporting bracket 85. The free end of the water reservoir raising arm 302 carries a roller 304, which engages the projection 305 on the underside of said water reservoir 264, by means of which the tappet 299 raises and lowers the water reservoir 264 as will be more fully described hereinafter. The reel of gummed strip paper 263 is carried by a bracket 306 secured to the frame A, the reel being carried on a stud 307 between the side supporting flanges 308.

The water reservoir 264 has a recess 309 starting with a curved end and extending toward its free end. The end of the gummed strip 263 is placed into said recess 309 passed under a pin 310 located in a recess 311; the pin causing a slight tension on gummed strip 263. The end is then passed between the lower surface of the member 278 and a brush 265 fixed in the water reservoir 264. The gummed strip is brought around the curved end 280 of the member 278 and then between the upward extending flanges 281. The tension weight 283 is placed in position resting on the gummed strip 263, said strip passing beneath the clamping arm 288 and being guided by the recess 285 in bracket 284, the end of said strip passing around the curved end 268 of bracket 284 to a receptacle not shown. As the gummed strip 263 passes between the underside of the member 278 and the brush 265, it is moistened passing around the curved end 280 of the member 278, and travels over the upper surface of said member, bringing the gummed strip in contact with the end of the band held on the band separator and conveyor F, and the return movement of the water reservoir causes a wiping action, and the gum is applied to the underside of the end of the band which is supported by a yielding cushion 69 provided for the purpose. A rocker arm 312 having a stud shaft 313 is mounted in a suitable bearing in magazine supporting bracket 85, the end 69 extending toward the band separator and conveyor F, and at a right angle thereto (see Fig. 24). The position of the extending portion 69 registers with the end 288 of the member 274. When the reservoir 264 has moved forward the extending portion 69 extends to and over the upright free arm 68 of the bell crank 66 of the emergency gum controlling device H. (See Fig. 3.) The free end of the rocker arm 312 extends toward the clamping arm 288 carrying angular member 314 so that when the clamping arm 288 is lowered, the said angular member engages the free end of the rocker arm 312, thus raising the supporting end 69. When the clamping

arm is raised the supporting end 69 is lowered by the spring 315, this position being limited by the stop 316 engaging a notch 317, except when there is no band to receive the gum; 5 in which case the downward movement is checked by the upright end 68 of the bell crank 66 of the emergency controlling device H.

The operation is as follows: starting with 10 the mechanism as shown in Fig. 7.

The band 71 on the band separator and conveyor F is in a position to be gummed. The action of the cam 18 of the worm-gear-clutch-unit rocks the bell crank 274, moving 15 the water reservoir 264 toward and under the extending end of the band 71, as shown in Fig. 8, the clamping arm 288 having clamped the gummed strip 263 to the bracket 284 causing the said strip to be advanced around the 20 rounded end 280 to the upper surface of the member 278, and the band supporting end 69 of the rocker arm 312 has been lowered, due to the raising of the clamping arm 288 by the cam 19 toward the end of the forward movement of the water reservoir (see Fig. 8). In 25 Figure 8 it will be seen that the water reservoir has reached its position toward and under the extending end of the band held on the separator and conveyor F. The clamping arm 288 has been partly raised and the rocker arm 312 is in its effective position; the end 69 forming the band support or cushion, resting 30 against the upper surface of band 71. Due to the action of the cam 19 of the worm-gear-clutch-unit and the bell crank 297, the tappet 293 raises the clamping arm 288 to its 35 extreme upward position and at the same time the tappet 299 raises the arm 302, thus raising the water reservoir 264 to its upward 40 or raised position against the underside of band 71 supported from above by the cushion 69. (See Fig. 9.) The reservoir 264 by means of the cam 18 of the worm-gear-clutch-unit moves away from the band 71 held on the 45 separator and conveyor F, transferring the gum from the moistened gummed strip 263 to the underside of the band by a wiping action. This leaves the mechanism as shown in Fig. 10. The water reservoir 264 is now in its lowered 50 position; the clamping arm 288 having been lowered and at the same time clamping the gummed strip 263 to the bracket 284, said downward movement of clamping arm raising the band cushion 69, thus bringing the 55 mechanism again in the position as shown in Fig. 7, thereby completing the cycle of operation. The clamping of the gummed strip 263 to bracket 284 during the movement of the reservoir toward the band 71, causes the 60 gum strip to be advanced, the clamping mechanism having remained stationary. The clamping mechanism is ineffective on the return movement of water reservoir 264 which carries the gummed strip 263 with it, the 65 used end of the strip passing out through the

recess 285 in bracket 284 to a waste receptacle, not shown in the drawings.

The discharge mechanism L comprises a reciprocating frame 320, the front end of which is pivotally connected to the arms 321 and 322 of the lever 323, secured to the rocker shaft 324 mounted in suitable bearings 325 and 326 in the frame A. Mounted on the outer end of the rocker shaft 324 is a cam lever 327, which is adjusted by means of a slot 328 and a bolt 329. The end of the cam lever 327 carries a cam roller 330 actuated by a cam 331, fastened on the main cam shaft 17. A spring 332 is attached to a spring post 333, fixed to the cam lever 327, the other end of which is attached to a spring post 334, secured in the frame A, said spring holding the cam roller 330 in contact with the cam 331, said cam causing the discharge mechanism L to reciprocate toward and away from the banding mechanism K intermittently. The rear end of the frame 320 carrying a bar 335 is mounted in a swivel bearing 336, pivotedly mounted on a stud 337, fixed in the bracket 338, fastened to the underside of the table B. 90

A member 234, secured on the rocker shaft 339 and mounted in the bearings 340, in frame 320 forms the lower gripping member 341 of the discharge mechanism L, said member 234 having a downwardly extending arm 342, carrying a spring post 343, to which is attached a spring 344, one end of which is attached to a spring post 345 on the under side of the frame 320. Said spring tends to keep the member 234 in its lowered position during its 100 travel toward the banding mechanism K.

Pivotedly mounted at 346 to the member 234 is a connecting rod 347, the lower end being pivotally connected to a cam lever 348, mounted on stud 349 fixed in the frame A. The cam lever 348 is actuated by a cam 350, secured on the main cam shaft 17. Said cam 350 with the aid of the spring 344 lowers the member 234 before it starts its travel toward the banding mechanism K. When the member 234 has moved to its position beneath the banding mechanism K, the cam 350 raises the member 234 and holds it in this raised position during its travel away from the banding mechanism K. The free end of member 234 forms the two lower gripping jaws 341, which when raised, extend slightly above the table B through the openings or slots 258. 110

Pivoted at 351, on the member 234, is an arm 352 having a spring 353 holding it in its raised position; this raised position being limited by a cross bar (not shown) coming in contact with the lugs (not shown) of member 234. The arm 352 extends toward and between the lower gripping jaws 341. Fas- 1 tened on the free end of arm 352 is a holder 356, adapted to hold a rubber finger 235. As the member 234 having the lower grip- ping jaws 341, is moved to its raised position, the arm 352 with the rubber finger 235

is also raised, coming up through the large opening 357, the two gripping jaws 341, and the rubber finger 235 coming up against the under side of the banded cigar. The lower gripping jaws 341 raise the cigar slightly up from table B, while the rubber finger 235 exerts a yielding pressure to the overlapping ends of the band wrapped around the cigar by the banding mechanism K.

10 In order to hold and remove the cigar from the banding position to the discharge position a pair of upper gripping members or fingers 236 and 237 are employed and operate in conjunction with the lower gripping jaws 341.

15 A bracket 358 secured to the frame 320 extends upward to which is secured a stud shaft 359 on which are pivotally mounted the upper gripping fingers 236 and 237. The finger 237 is held in its gripping position by a spring 360, one end of which is attached to a spring post 361 carried by the finger 237, the other end being secured in the bracket 358. The finger 236 is held in its gripping position by a spring 362 carried on the hub 20 of the finger 236, one end resting on the projection 363 of the finger 236, the other end being anchored in a collar 364 secured on a shaft 359. A link 365 having a slot 366 is pivotally attached at one end to the finger 237 by means of a stud 367, its other end being pivotally connected by a stud 369 to arm 368 which is pivotally mounted in the frame 320.

25 A link 370 pivotally connects the arm 368 with the member 234 so that when the member 234 forming the lower gripping jaws 341 is lowered, the upper fingers 236 and 237 are raised, and when said member 234 is raised toward the cigar the upper gripping fingers are lowered to the cigar. When the finger 237 is raised, a projecting lug 371 engages a lug 372 projecting from the finger 236. This raises the finger 236, and is so arranged that both fingers 236 and 237 will take an even grip on the cigar. Many cigars are thicker 30 at the tuck than at the head, and in this case the finger 236 will engage the cigar first, while finger 237 will continue to move down until it rests on the thinner end. The link 365 may still move up ineffectively owing to the slot 366; or, in other words, the downward movement of member 234 raises the fingers 236 and 237 to their extreme upward position, while the cigar, regardless of its thickness or diameter, limits the downward 35 movement of fingers 236 and 237, making it self-adjusting. This explains the first stage of the delivery operation. That is, the transferring of the cigar from the banding mechanism K to the discharging position. In order to deliver the banded cigars out on table B toward the box supporting shelf M, in a continuous layer or row, with each cigar in the same position in relation to each other as they were before being removed from the box, and so they will be returned to the box

in the same order as previously occupied, I employ the following: A stationary bracket 380, secured to the table B carries a stud 381 on which is pivoted a receiving member 382, extending toward the banding mechanism K. The free end of the member 382 is turned under and rests upon the cigar to hold it when the gripping members open and travel toward banding mechanism K. On the next cycle of operation, as the discharge mechanism L reaches its position to grip the next banded cigar, the member 234 is raised causing the closing of the gripping members. On member 234 are two upward extending lugs 383, which extend up through the openings or slots 258, in the table B, and so located on member 234, to cause them to come up between the cigar in the banding position and the one in the discharging position. When the discharging mechanism L moves away from the banding mechanism K, the gripping members remove the cigar from the banding position to the discharging position and the lugs 383 carry the cigar held in the discharging mechanism L together with cigars previously banded, a step further out on table B toward box supporting shelf M. As the cigars are carried by lugs 383 they pass from under the receiving member 382 to a second strip or member 384 which is pivotally connected by a link 385 to the first receiving member 382. The free end of the member 384 is suspended by a bolt 386 passing upward through the member 382, and is adjusted by means of a knurled thumb nut 387. Attached to the member 384 is a weighted ribbon 388, which keeps the cigars together and prevents them from turning while traveling out upon the table B.

40 The operation of the discharge mechanism is as follows:

45 With the machine in its normal or stop position, and a cigar in the discharge position under the receiving member 382, the lower and upper gripping members still gripping said cigar, and a layer of previously banded cigars under receiving member 384 and ribbon 388, the operator feeds a cigar into the banding position. The foot treadle is then tripped, starting the machine on its cycle of 50 operation, and while the banding mechanism K is descending and during the wrapping of the band about the cigar, the lower gripping jaws 341 are lowered, raising the upper gripping fingers 236 and 237. While said gripping members are in this position the discharging mechanism L moves toward the banding mechanism K. The lower gripping jaws 341 of the member 234 are raised against the underside of the cigar, the yielding rubber finger 235 also coming up at the same time. With the upward movement of said lower gripping jaws, the upper gripping fingers 236 and 237 have been lowered, thus gripping the banded cigar; the lugs 383, be- 55

ing positioned between the gripped cigar and the cigar held in discharge position. At this part of the cycle of operation the banding mechanism K is raised, relieving the cigar from the pressure of the platen. The discharging mechanism L now moves to the right or away from the banding mechanism K, delivering the banded cigar to the discharge position, while the lugs 383 carry the 10 previously banded cigar in the discharge position toward the right where it joins the layer or row of cigars under the members 382 and 384, thereby advancing the layer or row one step further out on table B toward box 15 supporting shelf M.

The operation of the machine, briefly, is as follows:

The operator removes the cigars from the cigar box and places the same in the hopper 20 D; then the operator sets the machine in operation by means of a foot treadle not shown, actuating a clutch arm and releasing a dog, said dog engaging the female clutch plate of a worm gear clutch unit, as a result of which, 25 the entire machine is set in operation. During the first cycle of operation, a band is taken from the band magazine. The operator then feeds a cigar into the gauged banding position and trips the foot treadle, starting 30 the machine on its second cycle of operation. During said cycle of operation the band is wrapped around the cigar, after which the cigar is moved from the banding position, to the discharge position, by means of the dis- 35 charging mechanism hereinbefore described. During the banding and discharging opera- 40 tion, the reciprocating separator and conveyor is also in operation, separating and removing the end band from the band maga- 45 zine, conveying it to the gumming position where the gum mechanism applies gum to one of its ends while the band is still on the conveyor; said conveyor then carrying it to the banding position where said band is wrapped 50 around the cigar, after which the cigar is moved to the discharging position, and by means of the discharging mechanism is dis- 55 charged from the machine. The cycle of operation just described is repeated continu- 60 ously as long as the pressure is applied to the foot treadle.

In the forepart of this specification I have stated that one of the objects of this invention is directed to mechanism adapted to 55 apply ungummed bands to cigars, but I wish it distinctly understood that my invention is not so limited, and that a machine embodying my invention will operate and function when gummed bands are used. If gummed 60 bands are used then the gumming or adhesive mechanism is utilized solely as a moistening mechanism, in which case the traveling tape will be moistened and when the said tape comes in engagement with the gummed band, 65 moisture will be applied to the gummed end.

When gummed bands are used the traveling tape will be ungummed.

In accordance with the provisions of the patent statutes, I have described the principle of my invention, together with the apparatus which I now consider to represent a practical embodiment thereof, but I desire it understood that my invention is not confined to the particular form of apparatus herein shown and described, the same being 70 merely illustrative, and that the invention can be carried out in other ways without departing from the spirit of my invention, and, therefore, I claim broadly the right to employ 75 all equivalent instrumentalities coming with- in the scope of the appended claims, and by means of which the objects of my invention are attained, and the new results accom- 80 plished, as herein set forth, as it is obvious 85 that the particular embodiments herein shown and described are only some of many that can be employed to attain these objects and accomplish these results.

Having described my invention, what I claim and desire to secure by Letters Pat- 90 ent is:

1. In a device of the character described having a band stack, a single means for removing a band from said stack and moving it to a position where said band is rendered ad- 95 hesive and thence to a second position where said band is applied to a cigar.

2. In a device of the character described having a band stack, a suction conveyor for removing a band from said stack and thence carrying said band to two operating positions, first, from said stack to a position where said band is rendered adhesive, and second, from said last named position to a position where 100 the said band is applied to a cigar.

3. In a device of the character described having a band stack, a single means for removing a band from said stack and thence carrying said band to two operating positions, first, from said stack to a position where 105 said band is rendered adhesive, and second, from said last named position to a position where said band is applied to a cigar, and means for holding said band stationary while it is being rendered adhesive.

4. In a device of the character described having a band stack, a single means for removing a band from said stack and thence carrying said band to two operating positions, first from said stack to a position where 110 said band is rendered adhesive, and second, from said last named position to a position where said band is applied to a cigar, and crimping means for holding said band sta- 115 tionary while it is being rendered adhesive.

5. In a device of the character described, means for delivering a band to an adhesive position, adhesive mechanism, and means for rendering said adhesive mechanism ineffective 120 125 130

when no band is in position ready to receive the adhesive.

6. A cigar banding machine comprising a band magazine adapted to hold a pile of bands, means for removing said bands one at a time, a member carrying a coating of adhesive, means for rendering the adhesive capable of separation from the member, means for transferring the adhesive from the member to the band, and means for moving the band to the banding position where the band is applied to a cigar.

7. In a cigar banding machine, band applying mechanism comprising means for conveying a band and conveying it to an adhesive position, a gummed tape, mechanism to operate said tape to apply gum to a portion of the band, and means to prevent contact between the gummed tape and the mechanism unless there is a band in position to have gum applied thereto.

8. In a cigar banding machine comprising a band magazine, adapted to hold a pile of bands, means for removing said bands one at a time, a ribbon carrying a coating of gum, means for feeding the ribbon to a band, means for moistening the gum, means for bringing a portion of the gummed surface in contact with the band, means for moving the ribbon relative to the band while still in contact therewith, means for holding the band against movement, and means for moving the band to the band applying position where it is applied to a cigar.

9. In a cigar banding machine having means for supporting a pile of bands and a single means for separating a band from the pile of bands and for conveying said band successively to a plurality of operating positions.

10. In a cigar banding machine having means for supporting a pile of bands and a single means having a depressed portion for separating a band from the pile of bands and for conveying said band successively to a plurality of operating positions.

11. In a cigar banding machine having means for supporting a pile of bands and a single conveyor having fluted portions for separating a band from the pile of bands and for conveying said band successively to a plurality of operating positions.

12. In a cigar banding machine having means for supporting a pile of bands and a conveyor having fluted portions and suction means on said conveyor for separating a band from the pile of bands and for conveying said band successively to a plurality of operating positions.

13. In a device of the character described having a band stack, a reciprocating conveyor for removing a band from said band stack and moving it to a position where said band is rendered adhesive and then to a position where said band is applied to a cigar.

14. In a device of the character described having a band stack, a reciprocating suction conveyor for removing a band from said stack and moving it to a position where said band is rendered adhesive and thence to a position where said band is applied to a cigar.

15. In a device of the character described having a band stack, a reciprocating conveyor for removing a band from said stack and thence carrying said band to two operating positions, first, from said stack to a position where said band is rendered adhesive, and second, from said last named position to a position where said band is applied to a cigar, and means for holding said band stationary while it is being rendered adhesive.

16. In a device of the character described having a band stack, a reciprocating conveyor for removing a band from said stack and thence carrying said band to two operating positions, first from said stack to a position where said band is rendered adhesive, and second, from said last named position to a position where said band is applied to a cigar, and crimping means for holding said band stationary while it is being rendered adhesive.

17. A cigar banding machine comprising a band magazine adapted to hold a pile of bands, a reciprocating conveyor for removing said bands one at a time, a member carrying a coating of adhesive, means for rendering the adhesive capable of separation from the member, means for transferring the adhesive from the member to the band, and means for moving the band to the banding position where the band is applied to a cigar.

18. In a cigar banding machine comprising a band magazine, adapted to hold a pile of bands, a reciprocating conveyor for removing said bands one at a time, a tapered member carrying a dry coating, means for moistening the coating, means for bringing the coated surface in contact with a band and transferring a portion of the coating from the member to the band, and means for moving the band to the band applying position where it is applied to a cigar.

19. In a cigar banding machine, band applying mechanism comprising a reciprocating conveyor for conveying a band and conveying it to an adhesive position, a gummed tape, mechanism to operate said tape to apply gum to a portion of the band, and means adapted to make contact between the gummed tape and the mechanism at such times as there is a band in position to have the gum applied thereto.

20. In a cigar banding machine comprising a band magazine adapted to hold a pile of bands, a reciprocating conveyor for removing said bands one at a time, a ribbon carrying a coating of gum, means for feed-

ing the ribbon to a band, means for moistening the gum, means for bringing a portion of the gummed surface in contact with the band, means for moving the ribbon relative to the band while still in contact therewith, means for holding the band against movement, and means for moving the band to the band applying position where it is applied to a cigar.

- 5 21. In a cigar banding machine, band applying mechanism comprising a reciprocating conveyor for conveying a band and conveying it to an adhesive position, a gummed tape, mechanism to operate said tape to apply gum to a portion of the band, and means adapted to make contact between the gummed tape and the mechanism at such times as there is a band in position to have the gum applied thereto.
- 10 22. In a cigar banding machine comprising a band magazine, adapted to hold a pile of bands, means for removing said bands one at a time, a tapered member carrying a dry coating, means for moistening the coating, means for bringing the coated surface in contact with a band and transferring a portion of the coating from the member to the band, and means for moving the band to the band applying position where it is applied to a cigar.
